Des. 228,758
Patented Oct. 23, 1973

228,758

RING MOUNTED DEFENSIVE BLADE

Charles Petrosky, 1118 Jefferson St.,
Arlington, Va. 22205

Filed Oct. 14, 1971, Ser. No. 189,485

Term of patent 14 years

Int. Cl. D22—02

U.S. Cl. D22—1

FIG. 1

FIG. 2

FIG. 3

FIG. 4

FIG. 5

FIG. 6

FIG. 1 is a perspective view of a defensive ring showing my new design;

FIG. 2 is an enlarged front elevation thereof;

FIG. 3 is a side elevation;

FIG. 4 is a rear elevation;

FIG. 5 is a top plan view; and

FIG. 6 is a bottom plan view thereof.

I claim:

The ornamental design for a ring mounted defensive blade, as shown.
